GRINDING COMBINATION AND DEVICE

William Favini, South Ozone Park, N. Y., assignor
or to Albert D. Mizzy, New York, N. Y.

Application July 1, 1941, Serial No. 400,612

11 Claims. (CL 51—105)

The invention relates to a grinding combination and a grinding device to be used to taper grind a rod or tube by the centerless grinding method. The combination and device to be described herein is particularly designed to be used for taper grinding tubular blanks to be made into hypodermic needles.

It is an object of the invention to construct a new and novel combination for grinding small diameter tubes and rods by the centerless grinding method.

Another object of the invention is to construct a grinding device which is particularly suited for centerless grinding of small diameter tubes and rods.

Another object is to construct a simple grinding device to be used to taper grind small diameter tubes or rods by the centerless grinding method, which device is adjustable to vary the angle of the taper.

A still further object of the invention is to construct a grinding device for grinding a small diameter rod or tube by the centerless grinding method, which device is adjustable laterally for controlling the amount to be ground from the rod or tube.

Other objects of the invention will be more apparent from the following description taken in connection with the accompanying drawing, showing a preferred embodiment of the invention, in which:

Figure 1 is an elevation of the grinding device in position adjacent the periphery of a grinding wheel and with a guide plate removed in order to show the groove which receives the work to be ground.

Figure 2 is a top view of the grinding device and grinding wheel.

Figure 3 is a section through the supporting block showing a centerless grinding seat or groove carried thereby and a rotatable chuck is holding a rod or tube to be ground in position ready for insertion in the groove where it will be rotated as it is ground.

The grinding device to be described herein is designed for small diameter tubing, or rods, which is supported throughout or substantially throughout its length because the rod or tube bends so easily. The combination provides a simple construction by which the tube or rod to be ground is rotated and is designed to obtain high production.

The grinding device includes a base 10 which is adapted to be secured in any suitable manner to a table or plate adjacent to a grinding wheel

11 carried upon and driven by a shaft 13. A post 12 extends vertically from the base to form an L-shaped frame.

A support 14 is mounted upon the frame in any suitable manner so as to obtain lateral adjustment thereof towards and away from the grinding wheel, whereby the depth of cut can be adjusted as desired. In the construction particularly illustrated, the support is slotted or forked so that the flanges formed thereby may pass over the base 10 and are pivoted thereto by means of a pin 15. Means are provided for adjusting the lateral position of the support upon the frame. This adjusting means comprises a screw 16 which is rotatably secured in the post 12 such as by means of a nut 17. The screw 16 is received in a threaded hole 18 in the support, so that rotation of the screw angularly adjusts the position of the support with respect to the post or frame. Ordinarily the angular adjustment of the support with respect to the frame need only be very little, and consequently the adjusting method illustrated is satisfactory. It is clear that if a greater degree of adjustment should be desired, a nut mounting may be provided upon the support so that the great angular variation of the support with respect to the screw or frame can be accommodated for.

The support 14 carries a block or rest 21 which has a groove 22 extending longitudinally thereof which receives the rod, tube or cylindrical part to be ground and supports the same during the grinding thereof. For grinding a taper, the groove 22 will taper as shown particularly in Figure 3. The groove has a relatively flat or horizontal portion for supporting the rod or tube and the side is inclined to provide a guide for the tube or rod. The rest may be tempered in order to resist wear.

The block or rest 21 is mounted upon the support 14 for angular adjustment thereupon. The mounting particularly illustrated includes a screw 23 which passes through a hole which preferably is located centrally of the rest and is threaded into the support so that the rest is rotatable or adjustable angularly upon the screw. Means are provided for adjusting the angular position of the rest 21 upon the support. The means particularly illustrated includes a pair of horizontally disposed screws 24 and 25 which are threaded into an upwardly extending flange carried by the support 14 and engage the back face of the block or rest, one on each side of the pivot screw 23. By loosening one screw and tightening the other, the angular position of the rest may

be adjusted at will. The advantage of the two screw adjusting means for the rest lies in the fact that the rest is firmly locked in adjusted position since one screw opposes the other. The screw 23 may also be used to assist in locking the rest or block in adjusted position.

Guide means is carried by the grinding device for guiding the rod or tube into the groove 22. The guide means particularly illustrated includes a plate 28 which may be suitably fastened to any part of the grinding device. The plate is shown as being secured to the end of the block 21 by means of a screw 29. A pin 30 may be used to hold the guide plate in proper position. The guide plate carries a guide hole 31 which directs the rod or tube into the groove 22.

The grinding device may be provided with a suitable stop for the rod or tube to be ground. The stop is shown as being a stop plate 33 which may be carried upon the other end of the block 21 and may be secured thereto by means of a screw 34 and pin 35. The end of a rod or tube T engages the stop plate 33 to prevent further insertion of the same into the block.

Either or both of the guide plate and stop may be otherwise mounted than upon the block 21 as desired in which case a mounting is required which will not obstruct or will permit a desired amount of angular adjustment of the block to be made. In such case too it is desirable that the guide hole be positioned in alignment with the groove 22.

The rod, tube or cylindrical part T is held in the chuck 37 which is rotated in any suitable fashion and its direction of rotation should be opposite to the direction of rotation of the grinding wheel 11. The chuck is movable towards the grinding block 21 so that the end of the tube or rod T passes through the guide hole 31 and into the groove or slot 22. The grinding wheel tends to force the tube or rod downwardly so that it rides upon the bottom or horizontal portion of the groove, the chuck rotating the rod or tube during the grinding operation. The inclined wall of the groove guides the rod, and since the groove is tapered, the tube T is guided at an angle with respect to the periphery of the grinding wheel and consequently it is ground with a taper. Preferably the chuck 37 is connected with a suitable flexible shaft 38 which in turn is connected with a motor or drive shaft (not shown), so that maximum flexibility is obtained for inserting the rod or tube to be ground into the chuck and maximum convenience in inserting the same into grinding position in the slot 22 through the guide hole 31.

Although the rest or grinding block 21 is shown with the horizontal part of the groove in down position, the block may be reversed, if desired, in which case the direction of the grinding wheel must be reversed so that the pressure of the wheel upon the needle presses the latter against the horizontal side of the groove. Since the needle to be ground is very fine, in fact about .010 of an inch or finer at its smaller end, the grinding block 21 engages or practically engages the grinding wheel. For this reason the face of the block preferably has a curvature corresponding with the curvature of the grinding wheel. For maximum wear the grinding block and stop are hardened.

This invention is presented to fill a need for improvements in a grinding combination and device. It is understood that various modifications in structure, as well as changes in mode of

operation, assembly, and manner of use, may and often do occur to those skilled in the art, especially after benefiting from the teachings of an invention. Hence, it will be understood that this disclosure is illustrative of preferred means of embodying the invention in useful form by explaining the construction, operation and advantages thereof.

What is claimed is:

10. A grinding combination comprising a rest having work supporting means to receive a cylindrical part to be ground by engaging the periphery thereof, means mounting the rest, means for adjusting the angular position and the forward position of the rest, a portable chuck for holding the cylindrical part to be ground and for rotating the same, a flexible shaft connected with the chuck so that it is movable for inserting the cylindrical part to be ground into the supporting means carried by the rest, and a guide means in alignment with the supporting means carried by the rest to guide the part to be ground.
15. A grinding combination comprising a rest having work supporting means to receive a cylindrical part to be ground by engaging the periphery thereof, means mounting the rest, means for adjusting the angular position and the forward position of the rest, a portable chuck for holding the cylindrical part to be ground and for rotating the same, a flexible shaft connected with the chuck so that it is movable for inserting the cylindrical part to be ground into the supporting means carried by the rest, and a guide means in alignment with the supporting means carried by the rest to guide the part to be ground.
20. A grinding combination comprising a rest having work supporting means to receive a cylindrical part to be ground by engaging the periphery thereof, means mounting the rest, means for adjusting the angular position and the forward position of the rest, a portable chuck for holding the cylindrical part to be ground and for rotating the same, a flexible shaft connected with the chuck so that it is movable for inserting the cylindrical part to be ground into the supporting means carried by the rest, and a stop at the end of the work supporting means.
25. A grinding combination comprising a rest having work supporting means to receive a cylindrical part to be ground by engaging the periphery thereof, means mounting the rest, means for adjusting the angular position and the forward position of the rest, a portable chuck for holding the cylindrical part to be ground and for rotating the same, a flexible shaft connected with the chuck so that it is movable for inserting the cylindrical part to be ground into the supporting means carried by the rest, and a guide means in alignment with the supporting means carried by the rest to guide the part to be ground, and a stop at the end of the work supporting means.
30. A grinding device for grinding a taper comprising a frame, a support adjustably carried by the frame, a rest pivotally mounted upon the support and having a groove of gradually decreasing depth in the face thereof and extending transversely thereof to support a part to be ground by engaging two points of the periphery thereof, and means to adjust the pivotal position of the rest and to lock the same in adjusted position.
35. A grinding device for grinding a taper comprising a frame, a support adjustably carried by the frame, a rest pivotally mounted upon the support and having a groove of gradually decreasing depth in the face thereof and extending transversely thereof to support a part to be ground by engaging two points of the periphery thereof, and means to adjust the pivotal position of the rest and to lock the same in adjusted position.
40. A grinding device for grinding a taper comprising a frame, a support adjustably carried by the frame, a rest pivotally mounted upon the support and having a groove of gradually decreasing depth in the face thereof and extending transversely thereof to support a part to be ground by engaging two points of the periphery thereof, and means to adjust the pivotal position of the rest and to lock the same in adjusted position.
45. A grinding device for grinding a taper comprising a frame, a support adjustably carried by the frame, a rest pivotally mounted upon the support and having a groove of gradually decreasing depth in the face thereof and extending transversely thereof to support a part to be ground by engaging two points of the periphery thereof, and means to adjust the pivotal position of the rest and to lock the same in adjusted position.
50. A grinding device for grinding a taper comprising a frame, a support adjustably carried by the frame, a rest pivotally mounted upon the support and having a groove of gradually decreasing depth in the face thereof and extending transversely thereof to support a part to be ground by engaging two points of the periphery thereof, and means to adjust the pivotal position of the rest and to lock the same in adjusted position.
55. A grinding device for grinding a taper comprising a frame, a support adjustably carried by the frame, a rest pivotally mounted upon the support and having a groove of gradually decreasing depth in the face thereof and extending transversely thereof to support a part to be ground by engaging two points of the periphery thereof, and means to adjust the pivotal position of the rest and to lock the same in adjusted position.
60. A grinding device for grinding a taper comprising a frame, a support pivotally carried by the frame, a screw carried by the frame for adjusting the position of the support with respect to the frame, a rest mounted upon the support for angular adjustment and having a groove of gradually decreasing depth to support a part to be ground by engaging the periphery thereof, means to adjust the angular position of the rest and to lock the same in adjusted position, a guide carried upon the end of the rest and in alignment with the groove to guide the part to be ground into the groove.
65. A grinding device for grinding a taper comprising a frame, a support pivotally carried by the frame, a screw carried by the frame for adjusting the position of the support with respect to the frame, a rest mounted upon the support for angular adjustment and having a groove of gradually decreasing depth to support a part to be ground by engaging the periphery thereof, means to adjust the angular position of the rest and to lock the same in adjusted position, a guide carried upon the end of the rest and in alignment with the groove to guide the part to be ground into the groove, and a stop carried upon the other end of the rest.
70. A grinding device comprising an L-shaped

frame including a base and a vertically extending portion, a support pivotally carried by the base of the frame, a screw carried by the vertically extending portion and engaging the support to adjust the position thereof, a rest mounted upon the support for angular adjustment in a horizontal plane and having a groove to support a part to be ground by engaging the periphery thereof, and means carried by the support to adjust the angular position of the rest and to lock the same in adjusted position.

7. A grinding device comprising an L-shaped frame including a base and a vertically extending portion, a support carried by the base of the frame upon a horizontal pivot, a screw carried by the vertically extending portion and engaging the support to pivotally adjust the angular position thereof with respect to the vertically extending portion of the frame, a rest pivotally mounted between its ends upon the support and having a groove to support a part to be ground by engaging the periphery thereof, and a screw engaging each end of the rest and carried by the support to adjust the position of the rest and to lock the same in adjusted position.

8. A grinding device comprising a frame, a support adjustably carried by the frame, means to adjust the position of the support upon the frame, a rest mounted upon the support for angular adjustment and having a groove to support a part to be ground by engaging the periphery thereof, means carried by the support to adjust the angular position of the rest and to lock the same in adjusted position, and means forming a guide for a rod or tube to be ground in alignment with the end of the groove.

9. A grinding device comprising a frame, a

support adjustably carried by the frame, means carried by the frame and engaging the support to adjust the position thereof, a rest pivotally mounted between its ends upon the support and having a groove to support a part to be ground by engaging the periphery thereof, a screw engaging each end of the rest and carried by the support to adjust the position of the rest and to lock the same in adjusted position, and means forming a guide for a rod or tube to be ground in alignment with the end of the groove.

10. A grinding device comprising a frame, a support adjustably carried by the frame, means carried by the frame and engaging the support to adjust the position thereof, a rest pivotally mounted between its ends upon the support and having a groove to support a part to be ground by engaging the periphery thereof, a screw engaging each end of the rest and carried by the support to adjust the position of the rest and to lock the same in adjusted position, means forming a guide in alignment with the end of the groove, and a stop means at the other end of the groove.

11. A grinding device for grinding a taper comprising a frame, a rest pivotally mounted upon the frame and having a groove to support a part to be ground by engaging the periphery thereof, the groove extending longitudinally of the face thereof, the groove having a side substantially at right angles to the periphery of the wheel and a guiding side at an angle thereto, the groove also having a decreasing depth from one end to the other, and means to adjust the pivotal position of the rest and to lock the same in adjusted position.

WILLIAM FAVINI.
